(74) Attorney, Agent, or Firm — Maceiko IP(22) Filed: **Sep. 11, 2012**(57) **CLAIM**(51) LOC (9) Cl. **09-03**

The ornamental design for a packaging device, as shown and described.

(52) U.S. Cl. **USPC ..... D9/427****DESCRIPTION**(58) **Field of Classification Search**

FIG. 1 is a top perspective view of a first embodiment of a packaging device showing my new design having a non-transparent bottom.

USPC D9/424, 425, 427, 429, 431; D7/530, D7/531, 608; 229/400-406, 932, 906.1; 220/656-659, 669-675, 912, 220/4.21-4.27; 206/499, 508, 557

FIG. 2 is an exploded top perspective view thereof.

See application file for complete search history.

FIG. 3 is a front elevation view thereof.

(56) **References Cited**

FIG. 4 is a right side elevation view thereof.

U.S. PATENT DOCUMENTS

FIG. 5 is a rear elevation view thereof.

D428,332 S	7/2000	Knutson	

FIG. 6 is a left side elevation view thereof.

FIG. 7 is a top plan view thereof.

FIG. 8 is a bottom plan view thereof.

FIG. 9 is a top perspective view of a second embodiment of a packaging device showing my new design having a transparent bottom.

FIG. 10 is an exploded top perspective view thereof.

FIG. 11 is a front elevation view thereof.

FIG. 12 is a right side elevation view thereof.

FIG. 13 is a rear elevation view thereof.

FIG. 14 is a left side elevation view thereof.

FIG. 15 is a top plan view thereof; and,

FIG. 16 is a bottom plan view thereof.

The paired, dot-dash, broken lines in exploded views, FIGS. 2 and 10, indicate the alignment of the design components.
